WIND STOP

George E. Miller, Cleveland Heights, Ohio

Application April 12, 1935, Serial No. 16,061

8 Claims. (Cl. 20—68)

This invention relates to wind stops, and more particularly to wind stops which are designed with special reference to use with the bottoms of doors. The general object of the invention is to provide a device of this character which is simple in construction and inexpensive of production; which may be readily applied to an object, such as a door, without the necessity for disfiguring or altering the construction of the latter; and which will effectually prevent the passage of any material amount of wind or water beneath the door to which it is applied.

I realize the foregoing objects in and through the construction and arrangement of parts illustrated in the accompanying drawing, wherein Fig. 1 represents an elevation of the lower portion of a door having my wind stop applied thereto; Figs. 2 and 3 are details in section corresponding respectively to the lines 2—2 and 3—3 of Fig. 1; and Fig. 4 is a perspective view of the form of spring which I prefer to use in connection with the swinging end of my wind stop.

The wind stop shown, described, and claimed herein is of the general type of that disclosed in my Patent No. 1,496,012, issued June 3, 1924, but embodies changes thereover which are advantageous in certain installations.

Describing the various parts by reference characters, I denotes the lower portion of a door which is hinged at 2 to one of the side frames or jambs 3. The door is shown as an inside door, no carpet strip or threshold being provided and there being a space beneath the bottom 4 of the door, which may receive carpeting or a rug.

My wind stop is slidably mounted on one side of the bottom of the door. It includes a supporting base member 5 (preferably a wooden strip) having a recess or rabbet 6 in its inner or door-facing side extending from the bottom toward the top thereof. Mounted in said recess or rabbet is the wind-excluding strip member 7, preferably of felt or rubber. The member 7 may be secured to the supporting base member 5 in any convenient manner, as by glue.

The parts 5 and 7 are mounted upon the bottom of the door by means of a wood screw 8 extending through the strip and into the door adjacent to the hinged edge of the same and by means of a U-shaped metal clamping frame extending beneath the bottom of the door adjacent to the swinging edge of the same. A spring washer 9 is interposed between the head of the screw 8 and the base member 5. The U-shaped clamping frame comprises two vertical branches 10 and 11 connected by the horizontal branch 12.

Each branch is provided at its upper end with a hook 13, 13^a by which the clamping frame may be raised and lowered.

The base member 5 is secured to the branch 10 by means of short bolts or rivets 14. Between the base member and the branch 10 there is interposed a flat leaf spring 15 having openings 15^a through which the bolts 14 extend. This spring has a flat intermediate portion which bears against the branch 10 and flexible end portions 10^b which engage the base member. By employing the spring 15, 15^a, 15^b, I am enabled to make the frame 10, 11, and 12 of comparatively heavy and rigid material.

It will be noted that the end of the strip 15 which is adjacent to the hinged edge of the door is rounded off, so as to permit the door to swing on its hinges without interference by said strip.

With the parts constructed and arranged as described, the operation will be readily understood. When the clamping frame is in the elevated position shown in Fig. 1, a space is provided beneath the strip 7 for circulation of air, said space extending a considerable distance from the swinging edge of the door toward the hinged edge 25 of the same. When it is desired to close this space, it is necessary only to push downwardly on either the hook 13 or the hook 13^a, thereby lowering the clamping frame and the wind-stop assembly to bring the lower edge of the member 7 into engagement with the floor.

The construction shown herein is useful, not only in connection with inside doors generally, but with doors of bathrooms, such as those employed in hotels, where it may often be necessary to employ some means for preventing water from the bath from passing beneath the door and injuring the rugs or carpeting in the rooms with which the baths are associated.

The attachment is practically universal, requiring only such variations in the length of the branches 10, 11, and 12 and of the stop as may be necessary to accommodate variations in the width and thickness of doors.

Having thus described my invention, what I claim is:

1. A wind stop applicable to the edge portion of a door and slideable thereupon and comprising, in combination, a U-shaped frame, a wind stop comprising a base and a strip carried thereby, the said base being secured to one of the parallel branches of the said frame, and a spring interposed between said branch and said strip.
2. A wind stop applicable to the edge portion

- of a door and slidable thereupon and comprising, in combination, a U-shaped frame, a wind stop comprising a strip secured to one of the parallel branches of the said frame, and a spring interposed between said branch and said wind stop. 5
3. A wind stop applicable to the edge portion of a door and slidable thereupon and comprising, in combination, a U-shaped frame, a base secured near one end thereof to one of the parallel branches of said frame, a strip carried by said base, a spring interposed between the said branch and the said base, and means for pivotally connecting the opposite end of said base thereof to the edge portion of a door. 10
15. 4. A wind stop applicable to the edge portion of a door and slidable thereupon and comprising, in combination, a U-shaped frame, a strip secured near one end thereof to one of the parallel branches of said frame, a spring interposed between the said branch and the said strip, and means for pivotally connecting the opposite end of said strip thereof to the edge portion of a door. 20
25. 5. A wind stop applicable to the edge portion of a door and slidable thereupon and comprising, in combination, a U-shaped frame, a base and a strip of pliable material carried thereby, the said base being secured to one of the parallel branches of the said frame, and a spring interposed between the said branch and the said base and anchored therebetween and comprising an elongated flat central portion and flexible end por-

tions deflected from the plane of the central portion.

6. A wind stop applicable to the edge portion of a door and slidable thereupon and comprising, in combination, a U-shaped frame, a strip carried thereby and connected to one of the parallel branches of the said frame, and a spring interposed between the said branch and the said strip and anchored therebetween and comprising an elongated flat central portion and flexible end 10 portions deflected from the plane of the central portion. 5

7. A wind stop as in claim 6 having the frame and spring connected thereto adjacent one end thereof, and means for pivotally securing the 15 opposite end thereof to the edge portion of a door.

8. A wind stop applicable to the edge portion of a door and slidable thereupon and comprising, in combination, a U-shaped frame, a base having 20 a rabbet extending upwardly from the bottom of one of the sides thereof, a strip of pliable material in said rabbet, a spring interposed between one of the branches of said frame and the opposite side of the said base, the said spring having an 25 elongated flat central portion and flexible end portions deflected from the plane of the central portion, and means securing the said base and the central portion of said spring to the said branch. 30
